ELECTROPLATING ANODE UNIT

William A. Crowder, Newark, N. J., assignor to
 Pyrene Manufacturing Company, Newark, N. J.,
 a corporation of Delaware

Application January 30, 1936, Serial No. 61,455

7 Claims. (Cl. 204—5)

This invention relates to electroplating apparatus, one of its objects being to make possible the use of an inexpensive filter unit by which undesirable constituents of the anode may be 5 trapped so as to prevent their being dispersed generally throughout the electrolyte, and another of its objects being to make possible the use of a relatively small electrolyte tank with attendant advantages such as conservation of space required for the apparatus as a whole and reduction 10 in the quantity of electrolyte necessary to enable the apparatus to function with efficiency.

To the above and other ends the invention 15 contemplates a tank having a metal lining of lead and carrying an electrolyte within which the article or articles to be plated may be suspended as cathodes and within which may also be suspended a plurality of anodes from which the plating material is derived, a slightly greater portion of each anode than its immersed length 20 being surrounded by a non-corrosive and non-conductive tube-like guard which is so perforated as to permit the passage of current from the anode only in a direction generally toward the article or articles to be plated and which for a portion of its submerged length is housed within 25 a non-conductive bag-like receptacle, of fibrous material, which is adapted, on the one hand, to permit passage of the ions of the metal to be deposited on the article or articles to be plated, and on the other hand, to obstruct and entrap 30 undesirable constituents of the anode, such as particles of graphitic carbon, so as to prevent their being dispersed generally throughout the electrolyte with deleterious results as they are freed from the anode incident to the carrying out 35 of the plating process.

Other objects and advantages of the invention 40 will become apparent from the following description, taken in connection with the accompanying drawings, in which—

Fig. 1 is a vertical, longitudinal, sectional view of an apparatus embodying the invention; Fig. 2 is a plan view of the apparatus; Fig. 3 is a fragmental, transverse, sectional view taken on line 45 3—3 of Fig. 2; Fig. 4 is an enlarged fragmental, sectional view of an anode unit; Fig. 5 is a transverse, sectional view taken on line 5—5 of Fig. 4, and Fig. 6 is a side view of an anode, drawn to 50 scale with reference to Figs. 1 to 3 and corresponding to the partially consumed anode illustrated in Fig. 5.

Referring to the drawings, the numeral 10 indicates a suitable tank having a metal lining 11, 55 of lead, and carrying an electrolyte E within

which one or more articles, generally indicated by the reference character A, may be suspended as cathodes and within which may also be suspended a plurality of anode units U.

The suspension means, for an article to be 5 plated, includes a suspension rod 12 to which an article to be plated may be suitably connected. The suspension rod 12 is formed at its upper end with a hook 14, by which it may be suspended from a rod-like support 15, mounted, for example, 10 on a pair of wing-like brackets 16 connected to the side walls of the tank 10. Preferably, the rod 12 is square in cross-section so that it, at its hooked end, will bite more or less into the support 15 and thus insure an effective electrical 15 connection between itself and such support.

The suspension means for each of the anode units U is substantially identical with the previously described article-suspension means in that it includes a suspension rod 17 formed at its upper end with a hook 18 by which it may be suspended from a rod-like support 20, mounted, for example, 20 on a pair of wing-like brackets 21 connected to the side walls of the tank, the rod 17 being preferably square in cross-section so that 25 it, at its hooked end, will bite more or less into the support 20 and thus insure an effective electrical connection between itself and such support.

Referring to the anode units U, it will be noted 30 that each of such units includes an anode 22 containing a plating material or materials as, for example, iron and/or nickel, the anode being adapted for screw-thread connection at its upper end to its corresponding suspension rod 11, as 35 shown most clearly in Fig. 1.

Associated with and surrounding each of the anodes 22 is a non-corrosive and non-conductive tube-like guard 24, preferably of hard rubber, which at its lower end extends a substantial distance beyond the corresponding end of the anode and which at its upper end protrudes a substantial distance above the level of the electrolyte E. That portion of the tube wall nearest the article or articles to be plated is rendered pervious, so 45 as to permit a flow of current through such wall in a direction generally toward the article or articles to be plated; and to that end the tube may be provided with slots or holes, the latter being employed in the present embodiment of the 50 invention and herein indicated by the numeral 25. Where a tube-like guard 24 having, for example, an outside diameter of 1½" is employed, the holes 25 may each be, for example, ¼" in diameter and spaced from each other ½" as meas- 55

ured from center to center. As illustrated in Fig. 4, the openings are distributed longitudinally of the guard throughout the major portion of its submerged length, but they, as illustrated in Fig. 5, are distributed arcuately of the guard over that portion of its peripheral area which is nearest the article or articles to be plated. While the arcuate extent of the perforations may be somewhat decreased according to conditions, it is believed that they, in keeping with their particular function to be hereinafter more fully described, should, in no event, exceed an arcuate distribution greater than the 180° distribution herein illustrated.

15 Enveloping each of the tube-like guards 24 throughout the major portion of its submerged length and entirely throughout the longitudinal extent of its perforated portion, is a non-conductive bag-like receptacle 26, of fibrous material, which is adapted, on the one hand, to permit passage of ions of the metal to be deposited on the article or articles to be plated, and, on the other hand, to obstruct and entrap undesirable constituents of the anode 22, such as particles of graphitic carbon, so as to prevent their being dispersed generally through the electrolyte with deleterious results as they are freed from the anode incident to the carrying out of the plating process. The bag-like receptacle 26 may be held in position on the guard 24 by the simple expedient of a rubber band or a draw-string 27, serving to constrict the upper or mouth-end of the receptacle into firm gripping engagement with the guard.

30 In order that the several tube-like guards 24 and their associated bag-like receptacles 26 may be held in definite positions with relation to the respective anodes which they envelope, there is provided a gang clamp 28 comprising a pair of complementary straps 30, each of which is shaped to present a plurality of equi-distantly spaced yokes 31. The corresponding yokes 31 embrace the upper ends of the individual tube-like guards 24 well above the liquid level of the electrolyte E and are there held in gripping or clamping position on such guards by drawing the straps 30 together and securing them to each other by a plurality of rivets 32, or the like, which pass transversely through both of such straps at points adjacent the several guards 24. The clamp 28 is supported as a unit by the simple expedient of a pair of hooks 34 connected to opposite ends of such clamp and suspended from the rod-like support 20.

35 From the foregoing it will be understood that when the anodes 22 and the article or articles A to be plated are connected, respectively, to the positive and negative terminals of a suitable source of electrical energy, not shown, a deposition of the plating material, for example, iron and/or nickel as derived from the anode 22, will be translated through the electrolyte E and deposited on the article or articles to be plated. The flow of current through the electrolyte will be in a direction generally toward the article or articles to be plated, as will be readily understood when it is taken into account that the resistance offered to the flow of current along such path is very substantially less than the resistance peculiar to an imaginary path from any anode to the metal lining 11 and thence from that lining to the article to be plated. Regarding the matter of difference in resistance, as just mentioned, it is to be observed from Fig. 2 that such difference is accounted for by reason of the fact that

the distances between any anode and the article or articles to be plated is substantially less than the shortest distance existing between an article to be plated and the metal lining 11 of the tank plus the shortest possible path existing between such lining and the anodes as a group, the length of which path is materially greater, due to the presence of the respective tube-like guards 24, than it would be in the absence of such guards, as will be readily appreciated when it is taken into account that the guards serve to block or prevent a flow of current from their respectively associated anodes except by way of the openings 25 which, in each instance, are formed in that portion of the tube wall nearest the article or articles to be plated and in no event exceed an arcuate distribution greater than 180°. Taking into account the fact that the length of the path from the anodes to the lining of the tank is substantially increased due to the presence of the guards 24, it becomes apparent that the walls of the tank may be located closer to the anodes than would be feasible in the absence of the guards and that the tank dimensions, especially the longitudinal dimension of the particular tank herein illustrated, may be kept at a minimum, thus conserving space required for the apparatus as a whole and reducing the quantity of electrolyte that would otherwise be necessary to enable the apparatus to function with efficiency. 30

In view of the fact that the guards 24 insure against an undesirable flow of current indirectly to the article or articles to be plated by way of the metal lining 11 of the tank, it is apparent that they are effective to not only insure against an 35 uneven deposition on the article or articles to be plated, but also to obviate possible contamination of such deposit under the influence of electrolytic action that would be induced as between the metal lining itself and the article or articles 40 to be plated.

Regarding the bag-like receptacles 26, the fact is here emphasized that they are so positioned on the tube-like guards 24 that they are wholly submerged within the electrolyte E at an appreciable distance below the surface thereof. Such disposition of the receptacles has been resorted to, because, in the development of the present invention, I discovered that even with an electrolyte only slightly acid in its character 45 receptacles of fibrous materials, such as canvas, could not be employed satisfactorily if they were so placed on the guards as to leave their upper ends exposed to the atmosphere above the level of the electrolyte, inasmuch as they would disintegrate along a definite line not coincident with the electrolyte level but a slight distance above the same. While such disintegration may be explained, generally speaking, by the fact that the liquid, which crept (because of capillarity) up 50 that portion of the receptacle which protruded above the electrolyte level, was subjected to the action of atmosphere, it may be well to here note the observations made by me when depositing iron through the medium of an electrolyte containing ferrous sulphate as one of its ingredients and when employing canvas receptacles so placed on the guards as to leave their upper ends exposed to the atmosphere. In that instance, such liquid as crept up the exposed portion of each 55 receptacle underwent evaporation and oxidation, with the result that crystals of ferric sulphate were formed, which, due to their highly corrosive nature, caused the receptacles to disintegrate after only a comparatively short period of time. 75

5 By the simple measure which I have resorted to, namely, so positioning the fabric receptacles on the respective guards that they are wholly submerged within the electrolyte at an appreciable distance below the surface thereof, I have overcome objectionable disintegration and have thus obviated the necessity of relatively expensive "filter pots", heretofore commonly employed.

10 Although only one form of the invention is herein shown and described, it will be understood that other changes may be made without departing from the spirit of the invention or the scope of the following claims.

15 What is claimed is:

1. In an electroplating apparatus containing an electrolyte, an anode unit including an anode partially submerged in the electrolyte, and a fibrous filter-receptacle enveloping the submerged portion of said anode only up to a point below the point to which the anode will be submerged in the electrolyte.

2. In an electroplating apparatus, an anode unit including an anode, a non-corrosive and 25 non-conductive guard surrounding said anode and extending upwardly beyond the point to which said anode will be submerged in the electrolyte, said guard having openings therein below the point to which said anode and said guard 30 will be submerged in the electrolyte, and a fibrous filter-receptacle covering said guard and the aforesaid openings therein up to a point below the point to which said guard will be submerged in the electrolyte.

25 3. In an electroplating apparatus, an anode unit including an anode, a non-corrosive and non-conductive guard surrounding said anode and extending from beyond the bottom of said anode upwardly beyond the point to which the 40 anode will be submerged in the electrolyte, said guard having openings therein below the point to which the anode and guard will be submerged in the electrolyte, and a fibrous filter-receptacle covering the bottom and perforated portion of said guard up to a point below the point to which said guard will be submerged in the electrolyte.

4. In an electroplating apparatus adapted to receive as cathodes the articles to be plated, an anode unit including an anode, a non-corrosive and non-conductive guard disposed in contiguous relation to the submerged length of said anode 5 and including an imperforate wall portion disposed on the side of said anode away from the article or articles to be plated.

5. In an electroplating apparatus adapted to receive as cathodes the articles to be plated, a 10 tank having a metal lining and adapted to contain an electrolyte, an anode unit including an anode, and a non-corrosive and non-conductive guard disposed in a contiguous relation to the submerged length of said anode and having an 15 imperforate wall portion on the side away from the article or articles to be plated and having a perforated wall portion on the side toward the article or articles to be plated.

6. In an electroplating apparatus adapted to 20 receive as cathodes the articles to be plated, an anode unit including an anode, a non-corrosive and non-conductive guard disposed in a contiguous and non-conductive relation to the submerged length of said anode, said guard having openings therein on 25 the side toward the article or articles to be plated, and a fibrous filter-receptacle enveloping the perforated portion of said guard and extending up to a point below the point to which said guard 30 will be submerged in the electrolyte.

7. In an electroplating apparatus adapted to receive as cathodes the articles to be plated, a tank having a metal lining and adapted to contain an electrolyte, an anode unit including an anode, a non-corrosive and non-conductive 35 guard disposed in contiguous relation to the submerged length of said anode, said guard having openings therein on the side toward the article or articles to be plated and having an imperforate wall portion on the side away from the 40 article or articles to be plated, and a fibrous filter-receptacle carried on and supported by said guard and enveloping only that portion of the guard which is below the point to which said guard will be submerged in the electrolyte.

WILLIAM A. CROWDER.
